INTERNAL COMBUSTION ENGINE

Application filed June 26, 1930, Serial No. 463,996, and in France June 27, 1929.

It is known that the thermo-dynamic efficiency of an internal combustion engine is greater, the higher the compression ratio.

In the case of engines in which the air for combustion and the fuel are mixed in a carburetor before entering the cylinder, however, the compression has to be limited to a rather low ratio in order to avoid premature ignition of the explosive mixture.

10 In the case of engines in which the fuel is injected directly into the engine cylinder by means of a special pump, either the compression ratio has to be made relatively low, if it is a question of engines in which ignition takes place by contact with a hot wall, or the adoption of high compression ratios necessitates the use of complicated and delicate pumps, if it is a question of engines in which ignition takes place as the fuel is injected into the cylinder.

According to the present invention, an attempt has been made to effect a method of supplying fuel to internal combustion engines which enables very high compression ratios to be selected without any disadvantages and without any complicated or delicate mechanism.

This method is characterized essentially by the fact that the fuel, before being injected into the engine cylinder to effect there its combustion, is subjected to two successive atomizing operations, by passing it at a high velocity through a single atomizer, first in one direction and a second time in the opposite direction.

The first passage of the fuel through the atomizer is due to the action of a portion of the air for combustion, strongly compressed by the engine piston, the said portion being caused to pass at a very high velocity, and just at the desired moment, through the said atomizer, into which the fuel has been introduced beforehand.

This fuel atomized once in this way is projected violently into an enclosed space, whence it may be returned in the opposite direction through the atomizer so as to undergo its second atomization before being injected into the combustion chamber of the engine cylinder and there to effect its com-

bustion in contact with the air for combustion, compressed by the engine piston.

This return of the fuel through the atomizer may be effected by various means.

Either a portion of this fuel, mixed with compressed air, may be ignited instantaneously and by any suitable means as soon as it arrives in the enclosed space so as to produce in the said enclosed space a very considerable increase in pressure, the effect of which is to force the rest of the fuel through the atomizer.

Or the atomized fuel, once it has been projected into the enclosed space, may be compressed by a piston, for example, or by any other mechanical means, thus being forced and injected again at a high velocity through the atomizer, without having undergone initial combustion.

Various devices may be used for putting the present method into operation.

A closure member is interposed between the combustion chamber of the engine and the enclosed space into which the fuel is injected after the first atomization, with the object of establishing, just at the desired moment, communication between the said chamber and the said enclosed space by the medium of the atomizer.

The moment at which communication is opened between the enclosed space and the combustion chamber may be adjusted by any suitable means while the engine is running and in accordance with the working of the said engine, so that, at the moment when the piston arrives at the upper dead centre, the combustion of the fuel, forced from the enclosure into the engine cylinder, is in full action.

The closure member may be formed for example of a valve or slide or distributor having a reciprocating or rotary motion, and the atomizer, of any known type, may be placed in the said closure member or outside thereof.

The enclosed space into which the fuel is injected after its first atomization may be constituted for example by a sort of closed antechamber of any suitable shape, and the ignition of a portion of the fuel in the said ante-

chamber may take place either by contact with the hot walls of the said ante-chamber, by electric spark, or by contact with the air for combustion which has been raised by compression to a high temperature.

On the other hand, in the case in which preliminary ignition of the fuel should not take place in the enclosed space, the latter may be formed of a simple cylinder in which a piston 10 is adapted to slide.

The fuel may be introduced into this enclosed space or directly into the atomizer under very low pressure or by the action of the vacuum prevailing in the engine cylinder during the suction stroke. It may also be introduced directly into the atomizer even when the latter is mounted in the closure member, in which case the fuel is introduced at the moment when the atomizer, by virtue of a 15 suitable movement imparted to the closure member, is situated opposite the fuel inlet opening.

It is easy to see that with the method of supplying fuel according to the invention, the 20 compression ratio may be made as high as possible according to circumstances, since there is no danger of preignition, the air and fuel being completely separated until combustion has to take place in the regular manner. An 25 engine working with this method of fuel supply will thus have an optimum efficiency.

The exact adjustment of the rate of flow of the fuel, which adjustment constitutes a problem that is almost incapable of solution when 30 the fuel is supplied by injection pumps of the usual design, may here be obtained by means of a simple needle valve, owing to the extreme simplicity of the various members and to the very low pressure required in order to introduce the fuel into the atomizer.

Various forms of construction of an internal combustion engine working according to the method conforming to the present invention are shown by way of example only 35 in the accompanying drawing.

In said drawing—

Fig. 1 is a sectional view showing the principal working parts of an engine constructed according to the invention;

Fig. 2 is a similar view of a modification;

Fig. 3 is a similar view of another modification; and

Fig. 4 is a fragmentary sectional view of still another modification employing a rotary 55 valve.

In Figure 1, 1 is the cylinder of a two-stroke cycle or four-stroke cycle engine, the distribution members of which for the gases are not shown. 2 is the piston and 3 is the 60 connecting rod. 4 is an ante-chamber, serving for the initiation of combustion, and which, at the desired moment, may be put into communication with the combustion chamber by means of a passage 5 closed by 65 a valve 6 controlled in known manner by the

engine. In the said passage 5 is located an atomizer 7 and the fuel may be introduced into this atomizer by the pipe 8 which is provided with any closure device in order to ensure tightness at the moment of combustion. 70 At the moment when the closure member 6 opens, a certain quantity of air for combustion, highly compressed by the engine piston 2, passes through the atomizer 7, and thus a first ultra-fine atomization of the fuel enclosed within the said atomizer is effected. The fuel thus atomized is projected with extreme violence into the ante-chamber 4 where a certain portion of the said fuel, after being mixed with air for combustion, ignites 80 instantaneously by contact with the walls of the ante-chamber, the said walls being kept hot by any known means.

The unburnt fuel in the ante-chamber 4 is sent back violently through the atomizer 7 by the hot gases produced under very high pressure by this partial combustion; the said unburnt fuel thus undergoes a second atomization before arriving in the combustion chamber 1 where combustion is completed. 90

In the form of construction shown in Figure 2, the atomizer 7 is situated directly in the closure member formed in this case by a slide 9, cylindrical or otherwise. The operation of introducing the fuel into the atomizer 7 is effected at the moment when the fuel delivery pipe 8 is situated, during the lateral displacement of the slide, opposite the hole 10 communicating with the atomizer. Afterwards, when the atomizer, owing to the lateral displacement of the slide in the reverse direction, is situated opposite the communication passage 11, a certain quantity of air for combustion, highly compressed by the engine piston 2, passes at a very high velocity 100 through the atomizer 7, where the first ultra-fine atomization thus takes place. Afterwards, the fuel thus atomized is projected violently against the hot walls of the ante-chamber 4 where partial combustion is initiated, the effect of which will be, as was explained hereinbefore, to cause the return through the atomizer, and the second atomization, of the unburnt fuel. 110

In the form of construction shown in Figure 3, it will be seen how the return of the fuel through the atomizer 7, with the view of the second atomization of the said fuel, may be effected not by a partial combustion in contact with the hot walls of the ante-chamber 4 as before, but by the action of a piston 12, movable in a chamber 13 into which the fuel enters after its first atomization. It suffices to move the said piston 12 at the desired 120 moment in the direction of the arrow shown in Figure 3 in order to force the fuel thus atomized through the atomizer 7, where it undergoes its second atomization before being injected into the combustion chamber of 130

the engine where it undergoes all its combustion.

In the form of construction shown in Fig. 4, the atomizer 7 is located, as in Fig. 1, in the passage 5; but the valve 9, in this instance, is of cylindrical form and of the rotary type. Said valve has a transverse passage 14, indicated by dotted lines, which is in line with passage 5 and which, by the rotation of the valve, registers therewith at the proper times to put the combustion chamber 1 in communication with said passage 5, as heretofore explained.

We claim:

- 15 1. A device for supplying fuel to internal combustion engines, comprising the combination of a closure member arranged between the combustion chamber of the engine cylinder and an enclosed space into which the fuel 20 is injected after its first atomization, an atomizer of any known type adapted to be put into communication at the desired moment with the combustion chamber and with the enclosed space by means of the closure member 25 suitably displaced, and a fuel admission pipe permitting the introduction of the said fuel into the atomizer.
2. A device as claimed in claim 1, in which the closure member is constituted by a valve 30 having rotary motion.
3. A device as claimed in claim 1, in which the atomizer is mounted between the closure member and the enclosed space.
4. A device as claimed in claim 1, in which 35 the atomizer is mounted in the closure member itself, in which case the fuel is introduced into the atomizer by displacing the closure member so as to bring the atomizer opposite the fuel admission pipe.
- 40 5. A device as claimed in claim 1, in which the fuel admission pipe is connected to the atomizer itself.
6. A device as claimed in claim 1 in which 45 the closure member is constituted by a valve having reciprocating motion.

In testimony whereof we have signed this specification.
